Specification of Letters Patent. Patented Jan. 11, 1921.

Application filed April 23, 1917. Serial No. 163,901.

To all whom it may concern:

Be it known that I, LIBANUS M. TODD, of Rochester, in the county of Monroe and State of New York, have invented certain new and 5 useful Improvements in Check-Writers; and I do hereby declare the following to be a full, clear, and exact description of the same, such as will enable any person skilled in the art to which the invention appertains to 10 make and use the same.

The present invention relates to printing apparatus and more particularly to a variety of hand stamp adapted for printing legends upon checks and other commercial papers 15 and commonly known as a "check writer."

One object of the invention is to provide a convenient machine of the class described, having few and simple parts and which will be reliable in operation and inexpensive to 20 manufacture.

Another object of the invention is to provide a machine of the class described, in which the usual automatic mechanism for feeding the work is replaced by a simple and 25 manually operated mechanism for accomplishing this operation.

These and other objects of the invention are fully described in the following specification, reference being had to the accompanying 30 drawings forming a part thereof and illustrating one embodiment of the invention, in which—

Figure 1 is a front elevation of the machine.

Fig. 2 is a side elevation of the machine.

Fig. 3 is a similar view partly broken away to show the feeding mechanism and other interior parts.

Fig. 4 is a sectional elevation substantially 40 on the line 4—4 of Fig. 3, with portions broken away to show interior parts.

Fig. 5 is a detail view showing the pawls and ratchet for actuating the feeding mechanism.

Fig. 6 is a detail view showing the pawl 45 springs for the feeding mechanism.

Fig. 7 is a detail view showing a spring detent for the feeding mechanism.

Fig. 8 is a detail view of the presser roll 50 device for holding the work.

Fig. 9 is a side elevation of the machine partly broken away, illustrating a modified form of feeding mechanism.

The present embodiment of the invention 55 comprises a casing for inclosing and sup-

porting the operating parts, having preferably a lower base portion 10 and an upper portion 11, partially separated from the lower base portion to form a work receiving slot 12 above a bed 13 on the base portion 60 10 for supporting the work.

A platen lever 14, Fig. 3, is supported for a rocking movement in a vertical plane by a shaft 15 journaled at its ends in the side walls of the base portion of the casing. The 65 forward end of this lever is provided with a head 16 in which is firmly supported in any convenient manner a platen 17 in the form of a bar, the upper side of which forms an impression surface. The work bed 13 is provided with a slot (not shown) through which this platen bar 17 is adapted to be raised for impressing the work against the type forms in the casing above, in the position shown in Fig. 3. The rear end of platen lever 14 70 75 has pivotally connected thereto at 18 a link 19 (Fig. 9) which is pivoted at 20 at its upper end to a crank plate 21 fixedly pinned to a shaft 22 rotatably journaled at its ends in the side walls of the rear of the upper 80 portion of the casing. This shaft 22 is the main operating shaft for the impressing mechanism and extends without the casing at one side thereof and has fixed thereon an operating crank 23, carrying at its end an 85 operating handle 24. In order to normally maintain the platen in lowered position, there is provided a spring 25 coiled about the shaft 22 and bearing at its ends against the crank plate 21 and the rear of the casing. 90 It will now be apparent that under the action of this spring, the platen is normally held in retracted position with the operating handle 24 in raised or initial position and that when the handle 24 is swung forwardly 95 and downwardly, the mechanism described will serve to raise the platen through the printing bed and press the work against the type forms in the casing above, which will now be described.

Journaled at its ends in the side walls of the upper forward portion of the casing is a shaft 26 having fixed thereon a type carrier or wheel 27 provided on its periphery with a plurality of separate type forms 28, 105 extending side by side in spaced relation parallel with each other and with the axis of the type wheel.

The present embodiment of the invention is herein shown as adapted for printing 110

upon checks, drafts and similar commercial papers, the exact amount for which such papers are drawn and expressed in words, as for example "Twenty one dollars seven cents." To this end the type forms 28 on the type wheel include a series of forms, each of which comprises the letters for printing a complete word expressing one of a range of numbers, as "One," "Two," 10 "Three," etc., these numbers being adapted for combination to express any desired monetary value within certain limits. There is also provided on the type wheel a type form for printing a line of stars, or other conventional limiting mark, to prevent the fraudulent addition of words at the beginning of a written amount. Also type forms are provided for printing the words "Hundred," "Dollars" and "Cents" and any other 20 characters which it may be desired to employ in this manner for printing a wider range of amounts or amounts expressed in different denominations.

One end of the type wheel shaft 26 is extended beyond the side of the casing and has fixed thereto a knob 29, conveniently formed for manually turning or setting the type wheel so as to bring the desired type forms 25 selectively and successively into printing position at the lower side of the wheel above the work bed 13. In order to indicate the position of rotary adjustment of the type wheel, or in other words, to show which of the type forms is in printing position, there 30 is provided an indicating device, comprising a dial 30, Fig. 1, formed on the periphery of one end of the type wheel and having thereon figures and other suitable symbols for representing the respective type forms, these 35 symbols on the dial being so arranged with reference to the type forms that when any given type form is in the printing position described, its corresponding symbol shows between the points 31 of the indicating 40 finger 32, fixed on the side of the casing and projecting adjacent the dial which is clearly visible through an opening 33 provided in the casing for this purpose.

In order to maintain the shaft 26 against 45 endwise movement in its bearings in the casing and also to simplify assembling, the shaft 26 is reduced at its left end where it passes through the casing in order to form a shoulder bearing against the inside of the 50 casing. Fastened to the reduced end of the shaft outside of the casing is a cap piece 35 resting against the casing, the cap piece and shoulder on the shaft coöperating to limit 55 endwise movement of the shaft in both directions.

To center and hold the type wheel with the selected type form in accurate printing 60 position, there is provided a bracket 36, Figs. 4 and 9, loose on the shaft 26 and held 65 against rotation on the shaft by means of

a screw 37, this bracket being formed with a substantially cylindrical chamber 38 having fitted therein a ball 39. A spring 40, pressing against the upper end of the chamber and against the ball, urges the latter outwardly into engagement with an annular series of centering notches 41 formed on the inner surface of a flange projecting at one end of the type wheel. These notches are so placed with reference to the corresponding type forms on the periphery of the type wheel, that when a given type form is moved approximately to printing position, the ball 39 is pressed by its spring into a corresponding notch and serves to draw the 70 selected type form accurately to printing 75 position and hold it in this position.

The means for inking the type forms comprises an ink roll 42, Fig. 3, journaled on a stud 43, fixed on and extending horizontally 80 from a bracket 44, pivotally supported on a spindle 45, carried by a bracket 46, which in turn is fixed on a cover plate 47. The latter is pivotally supported on the casing at 48 so as to close an opening 49 formed in the upper 85 wall of the casing, a finger piece 50 being provided for convenience in raising the cover plate and inking roll for obtaining access to the latter to clean or ink it. A spring 51 is provided, bearing against the cover 90 plate and against a lug 52 on the bracket 44 so as to urge the inking roll into position to contact with the type, when the cover plate is closed, during the rotation of the type 95 wheel. The ink roll is, for the sake of convenience, readily removable from the free 100 end of the stud 43.

The printing faces of the type and the impression surface of the platen may be corrugated or otherwise formed so that the fibers 105 of the paper will be disrupted and in condition to readily absorb the printing ink from the type faces and to become thoroughly impregnated thereby. The printing is thus incorporated into the body of the 110 paper itself and thereby made more difficult of erasure. A suitable construction for this purpose is disclosed in my prior Letters Patent of the United States, No. 793,249, granted June 27, 1905, so that a detailed description thereof is unnecessary herein.

The feeding mechanism preferably includes one or more rotary feed wheels 53, Fig. 3, a pair of such wheels being shown in the present case as carried by the hub 54, 120 fixedly pinned on the shaft 55, journaled in the frame work of the base portion of the casing. These feed wheels 53 project slightly at the tops of their peripheries through slots provided for that purpose in the printing 125 bed 13 so as to engage the under side of the work.

Fixed to the casing above the work slot is a bracket 56, Figs. 3 and 8, having extensions 57 carrying a spindle 58. Pivotally 130

supported on the spindle 58 is a lever 59, having at one end a convenient finger piece 60 and at its other end a pair of spaced lugs 61, carrying a spindle 62. Journaled on this spindle is a pair of presser rolls 63 adapted to bear against the upper side of the work and hold the same in contact with the feed wheels 53. One or both of these sets of rolls may be knurled to assist in gripping the work. A spring 64 is coiled about the spindle 58 and serves to urge the presser rolls 63 downwardly against the work. A slight pressure on the finger piece 60 serves, however, to raise the rolls 63 to permit the insertion or removal of the work.

The means for actuating the feed wheels 53 include a member or lever 65 pivotally mounted on a stud 66 projecting outwardly from the side wall of the casing. (Figs. 2 and 3.) The lever 65 extends parallel with the side of the casing and has its forward end shaped to form a finger piece 67 extending forwardly and outwardly from the casing so as to be readily accessible. The rear end of this lever carries a bracket 68 pivotally supported thereon by means of a pin 69 and provided with a pair of spaced lugs 70. Pivotally supported by these lugs are a pair of depending pawls or racks 71 and 72, Figs. 3 and 5. The pawl 71 has fixed in its lower end a stud 73 which extends loosely through a slot 74 in pawl 72 and is provided with a head so that each of these pawls is guided at its lower end by the other through the action of the stud 73. Fixed to the side of the casing is a spring clip 75, Figs. 4 and 6, having a pair of resilient fingers 76 extending inwardly and bearing against the outer edges respectively of the pawls 71 and 72, so as to hold each pawl with its toothed edge in engagement with the ratchet wheel 77, fixed on the shaft 55.

It may be seen by reference to Fig. 5, that the teeth of pawls 71 and 72 are relatively staggered so that each tooth on pawl 72 is opposite the middle of the interval between the teeth on the pawl 71; thus but one of these pawls is in actuating mesh with the ratchet wheel at a time, but the staggered arrangement of the teeth serves to provide teeth for engagement with the ratchet at one-half the interval between the teeth on either pawl alone, this in effect producing teeth of a finer pitch than could be provided in practical construction and serving to decrease the extent of any lost motion between the ratchet and the pawls when the latter are moved to engage and move the ratchet.

A second spring clip 78, Figs. 3 and 7, is fixed to the bottom of the printing bed and is provided with resilient fingers 79 which engage the teeth of the ratchet wheel 77 to serve as a detent to prevent reverse rotation of the shaft 55. Fingers 79 are offset relatively to each other in the same manner and

for the same purpose as in the case of the teeth of pawls 71 and 72. It will be noted that as the bracket 68 is supported for pivotal movement in the plane of the lever 65, and the pawls 71 and 72 are supported for swinging movement in a plane at right angles to the plane of movement of the bracket, there is thus formed, substantially, a universal joint which insures an unrestricted vertical movement of the pawls under the actuation of the lever 65.

A spring 80 (Fig. 2) coiled about the stud 66, is attached at one end to the casing and bears at its other end upon the lever 65 so as to hold the latter yieldingly with its finger piece 67 in raised position. When the finger piece is manually depressed, it will be apparent that the pawls 71 and 72 are raised, without turning the ratchet wheel 77, into position for rotating the latter however, under actuation of the spring 80 when the finger piece 67 is released.

The releasing of the finger piece therefore permits the spring 80 to rotate shaft 55 and the feed wheels 53 fixed thereon, the latter serving to feed the work which is held in engagement with their peripheries by the presser rolls 63. In this manner the work is fed between the printing members, in the direction of the reading line, between the printing impressions for the purpose of providing a new space for each impression. As the words printed are of varying length, as for instance, the words "One" and "Seventeen," it is necessary to control the extent of rotation of the feeding wheels in connection with each impression in accordance with the length of the particular work impressed and the means for this purpose will now be described.

The cap or hub 35, fixed on the exterior end of shaft 26, has fixed thereon a gage plate or disk 82 having in its periphery a plurality of shoulders or stops extending varying radial distances from the center of shaft 26. Each one of these shoulders or stops corresponds with one of the type forms and its radial distance from the center of shaft 26 is inversely proportional to the length of its respective type form; that is to say, for the longer type forms, such for instance as that for printing the word "Seventeen," there are provided stops at lesser radial distances from the shaft 26 and vice versa. Coöoperating with the shoulders of the gage 82 is a finger 83, (Figs. 3 and 4), projecting above the gage and guided for vertical movement toward and from the latter by engagement in the slot 84 formed in the casing. This finger 83 projects from the plate 85, which has formed in its center portion, an elongated slot 86 engaging about the cap 35, fixed on the shaft 26, so as to be guided during its vertical movement by the cap. The lower

105

115

120

125

130

end of plate 85 is provided with an extension 87 in which is fixed a small stud or pin 88, engaging a slightly elongated opening in the lever 65 so that during the reciprocation of the latter, the plate 85 is given a guided vertical movement by the lever. Upon the depression of lever 65, the finger 83 is moved downwardly into engagement with the stop shoulder of the gage corresponding to the particular type form in printing position, thus limiting the downward movement of lever 65, and consequently the upward setting movement of the pawls 71 and 72, and thus controlling the extent to which the feed wheels 53 are rotated upon release of the actuating lever, as the latter, upon its release and subsequent ascent, comes to a fixed position, determined by the contact of the lever with the cap 35. Thus if a short word, such as "One" is brought to printing position and impressed upon the paper, and the lever 65 then depressed, finger 83 engages with one of the higher stop shoulders of the gage and thereby limits the reciprocating movement of the actuating lever 65 and controls the extent of rotation of feed wheels 53 so that the work is fed a small distance in accordance with the short length of the word printed. If, however, one of the longer words has been selected for printing, the gage 82 has thereby been set or adjusted so that the finger 83 strikes one of the lower stops of the gage, which permits a greater movement of the lever 65 and consequently a greater rotation of the feed wheels 53.

For the purpose of assisting in the location of the work in the work receiving slot so that an impression will be made on the desired line of the work, there is provided a pair of spaced lugs 89 projecting upwardly through slots in the printing bed from a sliding plate 90 loosely supported against the lower side of the printing bed and manually adjustable to different distances from the front of the machine, so that the lugs 89 may be adjusted to serve as guides during the insertion of the work and to keep the latter moving in a straight line during the feeding movement. The means whereby the plate 90 is adjustably held is not shown and described herein as any one of a number of devices known in the art for permitting such sliding adjustment may be used.

To inclose and protect parts of the feeding mechanism there is provided a guard 91 fixed to the upper portion of the casing, as best seen in Fig. 2. Also to assist in retaining the plate 85 in proper working position there is formed on the plate a lug 92 (Figs. 3 and 4), which, during the sliding movement of the plate, is in contact with the inner surface of the guard 91.

The operation of the machine will be clear from a brief explanation in connection with the above description of its construction. The finger piece 60 having been depressed to raise the presser rolls and the work having been located in the machine, with its edge against the guide lugs 89, and in position to receive the impression of the first character, the type wheel is then adjusted by means of the knob 29 and with the aid of the indicating device, to bring the initial type form to printing position. This setting of the type wheel, as explained, also sets the gage 82 to control the feeding movement. The operating handle 24 is then pulled forwardly, thereby straightening the toggled link 19, rocking the platen lever, and raising the platen so as to press the work against the type form above, which has been inked during the setting movement of the type wheel by the inking roller 42. The operating lever is then released and spring 25 retracts the platen, freeing the work for the feeding operation, which is produced by the actuation of the finger piece 67 of lever 65. The rocking of this lever sets the pawls 71 and 72 to a position controlled by contact of finger 83 with gage 82, and upon release of finger piece 67 spring 80 returns actuating lever 65 to initial position, and the pawls 71 and 72 rotate the ratchet wheel 77 and feed wheels 53, thus advancing the work the proper distance. The next word is then selected and impressed in the same manner until the entire legend has been printed upon the paper, after which the finger piece 60 is depressed to release the work, which is then withdrawn with the desired legend impressed thereon.

A modified form of construction of the feeding mechanism is illustrated in connection with Fig. 9. In this construction the shaft 93, carrying the feed wheels 53, is extended forwardly through the front of the lower portion of the casing and is there provided with a knob 94 suitable for rotation by hand to rotate the feeding wheels and feed the work. In this form of construction the gage for determining the extent of feed is omitted and the extent of feeding movement is determined directly by sight, the printing point being partially visible from the left side of the machine so that the work may be fed until the last word printed is carried out of printing position and a new space provided at the proper interval for the next word. The same form of presser rolls for the work and means for raising the same are provided as in the preferred construction. The type wheel shaft 26 in this construction is held against endwise movement in the casing by a retaining plate 81 secured to the casing and formed to engage in a recess 81^a in the end of the shaft, thereby locking the shaft in position.

Having thus described my invention, what I claim as new, and desire to secure by Letters Patent is:—

1. In a printing apparatus, a type carrier provided with a plurality of type forms of varying lengths and a platen common to said forms, means for determining the type form to be printed from and effecting a relative movement of the type carrier and platen to print, a gage movable as an incident to determining the type form to be printed from, a differentially rotatable work feeding wheel, a manually operated member and actuating connection between said member and the feeding wheel, and a device connected to the manually operable member and coöperating with the aforesaid gage to differentially limit the extent of rotation of the feeding wheel.
2. In a printing apparatus, a type wheel movable to bring a plurality of type forms of varying length, selectively, to printing position, a platen for individual coöperation with said type forms; operating means for effecting a relative impressing movement of said type wheel and platen; a gage movable with said type wheel; a rotary feed wheel; a pivotally mounted member provided with a finger piece for manual operation; an actuating connection between said pivotally mounted member and said feed wheel; and a device connected with said pivotally mounted member and coöperating with said gage for controlling the extent of rotation of said feed wheel according to the length of the type form printed.
3. In a printing apparatus, a type wheel rotatable to bring any one of a plurality of type forms of varying lengths to printing position, a platen coöoperating with the form at said position, means for effecting a relative printing movement of the type wheel and platen, a gage adjustable to different positions by turning the type wheel, a rotary feed wheel, a manually operable pivoted lever, an actuating connection between the pivoted lever and the feed wheel, and means carried by the pivoted lever and coöperating with the aforesaid gage for determining the extent of rotation of the feed wheel.
4. In a printing apparatus, a type wheel rotatable to bring any one of a plurality of type forms of varying lengths to a common printing position, a platen coöoperating with the form at said printing position, means for effecting relative printing movement of the type wheel and platen, a gage movable as an incident to rotating the type wheel, a differentially rotatable work feeding wheel, a manually operable centrally pivoted lever, an actuating connection between said pivoted lever and the feed wheel, and a device connected to the lever and coöperating with the aforesaid gage to limit the movement of the lever in one direction whereby to regulate the extent of movement imparted to the feed wheel.
5. In a printing apparatus, the combination with a type carrier adjustable to bring a plurality of type forms of varying lengths selectively to printing position, a platen coöperating with the type form at said position, means for effecting a relative printing movement of the type carrier and platen, a gage set by adjustment of the type carrier, a rotary work feeding wheel, a manually operable element, means whereby the gage differentially limits the extent of movement of the manually operable element, and connections for transmitting the differential movement of said element to the work feeding wheel.
6. In a printing apparatus, the combination of a type carrier adjustable to bring a plurality of type forms of varying lengths selectively to printing position, a platen coöperating with the type form at said position, means for operating the platen to take impressions from the type at said position, a gage movable with and in axial alinement with the type carrier, a differentially rotatable work feeding wheel, a manually operable lever, means coöperating with the gage for differentially limiting movement of the manually operable element and connections including a ratchet and pawl for transmitting said differential movements to the rotary work feeding device.
7. In a printing machine, a rotatable work feeding wheel, a ratchet wheel rigid therewith, a manually operable member, a pair of racks carried by the manually operable member and coöperating with the ratchet wheel, the teeth of the two racks being staggered with reference one to the other to permit engagement of either but not both with the ratchet.
8. In a printing machine, a rotatable work feeding wheel, a ratchet wheel rigid therewith, a manually operable member, a pair of racks carried by the manually operable member and coöperating with the ratchet wheel, the teeth of the two racks being staggered with reference one to the other to permit engagement of either but not both with the ratchet, and a retaining device coöperating with said ratchet and having ratchet engaging portions offset with reference to each other whereby to permit engagement of either but not both portions with the ratchet.
9. In a printing apparatus, a type carrier provided with a plurality of type forms of varying lengths and a platen common to said forms, means for effecting relative movements of the type carrier and platen to determine the type form to be printed

from and to print from the determined form, a gage movable as an incident to determining the type form to be printed from, an element differentially movable in engagement with the work to feed the work between the type carrier and platen, a manually operable member and connections for actuating said work feeding element, and means moving with the manually operable member and coöperating with the aforesaid gage to limit differentially the movements of the member and work feeding element.

10. In a printing apparatus, a type wheel movable to bring a plurality of type forms of varying lengths, selectively, to printing position, a platen for individual coöperation with said type forms, operating means for effecting relative impressing movement of the type wheel and platen, a gage movable with said type wheel, an element movable in engagement with the work to feed the work between the type wheel and platen, a movable member provided with a finger-piece for manual operation, an actuating connection between said member and said feeding element, and a device actuated by the manually operable member and coöperating with the gage for controlling the extent of movement of the feeding element according to the length of the type form printed from.

11. In a printing apparatus, the combination with a type carrier provided with type forms of various lengths and a platen common to said forms, of means for effecting relative movements of the type carrier and platen to select the type form to be printed from and to print from the selected form, manually operable mechanism for feeding the work between the type carrier and platen between impressions, and a work feed controlling gage set by the type selecting means for controlling the extent of the feeding movements of said mechanism according to the lengths of the type forms printed from.

12. In a printing apparatus, the combination with a type carrier provided with type forms of varying lengths and a platen common to said forms, of means for effecting relative movements of the type carrier and platen to select the type form to be printed from and to print from the selected form, a gage adjustable as an incident to selecting the type form to be printed from, an element differentially movable in engagement with the work to feed the work be-

tween the type carrier and platen, and devices manually operable under the control of the gage for effecting the differential movements of the work feeding element. 60

13. In a printing apparatus, the combination with a type carrier provided with a plurality of type forms of varying lengths and a platen common to said forms, of means for effecting relative movements of the type carrier and platen to select the type form to be printed from and to print from the selected form, a work feed controlling gage automatically adjusted in selecting the type form to be printed from, a lever manually movable to varying extents depending upon the adjustment of the gage, and work feeding mechanism connected for actuation by said lever. 70

14. In a printing apparatus, the combination with a type carrier provided with a plurality of type forms of varying lengths and a platen common to said forms, of hand operated means for effecting relative movements of the type carrier and platen to select the form to be printed from, hand operated devices for effecting relative printing movements of the type carrier and platen, a work feeding gage adjustable to different controlling positions by the type selecting means, and hand operated work feeding mechanism for feeding work between the type carrier and platen, the movements of said feeding mechanism being variably controlled by the work feeding gage. 90

15. In a printing apparatus, the combination with a platen, of a type carrier provided with type forms of different lengths and adjustable to set any desired form opposite the platen, a work feeding gage provided with feed controlling portions graduated to correspond with the lengths of the type forms and adjustable to set any desired portion at a controlling position, common means for adjusting the type carrier and gage, means comprising a hand operated member for effecting relative movements of the type carrier and platen to make impressions, and means comprising a hand operated member movable to different extents depending upon the portion of the gage in controlling position for feeding the work between impressions. 95 100 105
